Specification for Design.

Patented Sept. 28, 1915.

Application filed July 10, 1914. Serial No. 850,266. Term of patent 7 years.

To all whom it may concern:

Be it known that I, RICHARD C. SCAIFE, a citizen of the United States, residing at Cleveland, in the county of Cuyahoga and State of Ohio, have invented a new, original, and ornamental Design for a Steering-Column Switch Unit, of which the following is a specification, reference being had to the accompanying drawing, forming part thereof.

Figure 1 is a side view; Fig. 2 is a side view looking toward the opposite side; Fig.

3 is an end view; Fig. 4 is an end view looking toward the opposite end; and Fig. 5 is a top plan view of a steering column switch unit showing my new design.

I claim:

The ornamental design for a steering column switch unit substantially as shown.

RICHARD C. SCAIFE.
